His Attorney.

UNITED STATES PATENT OFFICE

WALTER KLEINOW, OF HENNIGSDORF, NEAR BERLIN, GERMANY, ASSIGNOR TO
GENERAL ELECTRIC COMPANY, A CORPORATION OF NEW YORK

BURNER FOR PULVERULENT FUEL

Application filed January 9, 1929, Serial No. 331,341, and in Germany January 14, 1928.

My invention relates to burners for pulverulent fuel for furnaces of the kind described in U. S. Patent No. 1,739,035, granted December 10, 1929, by myself jointly with Albert 5 Morgenroth, Friedrich Reinhardt, Wilhelm Bruer. As described in the application aforesaid it is desirable to provide efficient cooling means for the burners. It is an object of my invention to improve such cooling means. To this end I provide instead of a water cooling system for the burner a heat abducting member of some suitable substance having high heat conductivity for instance of a metal such as copper and I connect this member with the burner so as to exert thereon the desired cooling action.

Preferably the heat abducting member is connected with the boiler. In a locomotive boiler it may for instance be secured to the 20 foundation ring of the fire box, and preferably the discharge slots for the mixture are formed in it.

The water cooling system described in the patent aforesaid is efficient but it involves a 25 certain amount of complication which may cause trouble and also interferes with the ready inspection of the furnace. These drawbacks are eliminated by the present invention, in which the desired effect is achieved without water piping and heating of the slot walls to such an extent as to cause backfiring and damage to the walls is eliminated.

In the preferred embodiment of my invention which will be described hereinafter, the 30 heat abducting member, which may be made of copper, is of angular or channel section, is connected with the supply conduit for the mixture and attached to the boiler. In this manner the heat from the walls of the discharge slots is rapidly and readily transferred to the boiler and to the water in the 35 boiler. As mentioned above, in boilers of the locomotive type the member is secured to the foundation ring of the fire box.

The discharge slots for the mixture are 40 preferably made in the member by milling or by some other suitable process and so that the walls of the slots are integral with the body which also favors intense heat dispersion.

In the drawings affixed to this specification and forming part thereof my invention is illustrated as applied to a locomotive fire box, one of the water legs and the adjacent frame of the locomotive being shown. Figure 1 represents a transverse section, Figure 2A represents a fragmentary horizontal section along line 2A—2A of Figure 1 and Figure 2B represents a fragmentary horizontal section along line 2B—2B of Figure 1. 55

Referring to the drawings, 2 is the inner shell of the fire box which is secured to the foundation ring 2' in the usual manner, 42 is the combustion chamber below the fire box, 41 is the ash tray and 11 is the lining of the combustion chamber which is secured to the walls of the ash tray 41 and partly extends into the fire box 2. 60

The lining 11 is slotted for the reception of the burner unit. The unit comprises a conduit 7 to which the mixture is supplied as described in the said patent and which is secured to a heat abducting member 61 of angular section, the horizontal flange of which is attached to the foundation ring 2'. 70

As mentioned above, the member 61 is preferably made of copper. The conduit 7 is provided with a cover plate 20', having slots 15, which may be inserted in a recess of the flanged conduit 7 and held in position by the vertical flange of the member 61. The member 61 is slotted at 16, preferably by milling. 75

In this manner the heat from the slots 16 is transferred to the water space of the boiler through the member 61 and the foundation 80 ring 2', and the slots are efficiently cooled.

With the member 61 as illustrated to replace the water piping described in the said patent, the size of the burner unit is much reduced and the heating surface of the combustion chamber is conserved in proportion. The unit is arranged very conveniently between the frame plates 62 of the locomotive and the combustion chamber 42. 90

I wish it to be understood that I do not desire to be limited to the exact details of construction shown and described for obvious modifications will occur to a person skilled in the art. 95

In the claims affixed to this specification no 100

selection of any particular modification of the invention is intended to the exclusion of other modifications thereof and the right to subsequently make claim to any modification not covered by these claims is expressly reserved.

5 I claim:—

1. The combination of a locomotive boiler having a wall defining a part of a liquid space, a fuel burner for supplying fuel for heating 10 said boiler, said burner comprising a plate formed from a material having a high heat conductivity and provided with discharge slots, and means thermally connecting said plate to said wall for conducting heat from 15 the plate to said wall.

2. The combination of a locomotive boiler, a fuel burner comprised of a fuel conduit and a face plate provided with discharge passages through which fuel for heating the said boiler 20 is emitted, a second plate formed of material having a high heat conductivity attached to said first-named plate between the combustion chamber and the burner, and means for thermally connecting said last-named plate 25 to a heat absorbing portion of the boiler.

3. The combination of a locomotive boiler having a water leg and a foundation ring, a pulverulent fuel burner comprised of a pulverulent fuel conduit and a slotted face plate 30 for supplying fuel to heat said boiler, a second slotted plate formed of high heat conducting material connected to the first-named plate, and means thermally connecting said last-named plate to the foundation ring.

35 4. The combustion of a locomotive boiler having a wall, of a combustion chamber comprising a side wall and a pulverulent fuel burner extending along said side wall and having a slotted face through which the pulverulent fuel is supplied to said combustion chamber, and a heat conducting metal sheet 40 connecting said burner face with the outer wall of said boiler.

45 In testimony whereof I affix my signature.

WALTER KLEINOW.
